UNITED STATES PATENT OFFICE.

WILLIAM S. PHELPS, OF SAN FRANCISCO, CALIFORNIA.

CABLE OR ELECTRIC STREET-RAILWAY.

SPECIFICATION forming part of Letters Patent No. 397,385, dated February 5, 1889.

Application filed August 4, 1888. Serial No. 282,003. (No model.)

To all whom it may concern:

Be it known that I, WILLIAM S. PHELPS, of the city and county of San Francisco, State of California, have invented an Improvement 5 in Street-Railways, of which the following is a specification.

The invention relates to the substructure of the crossings and junctions of those railways which have sub-surface tunnels or tubes to 10 give passage to part of the car mechanism, as the grip of a cable railway or the collector of an electric railway.

The invention consists in the combination of parts constituting what are called the 15 "points"—*i.e.*, the portion of the substructure between the two intersecting or joining slots through which the grip or collector shank passes from the point where the two slots intersect or join each other to a short distance 20 back, whereby these points are made more substantial than heretofore and capable of being adjusted both horizontally and vertically, so that when they become displaced, by reason of heavy loads passing over them, they 25 may in a simple manner, without reconstruction or repairs, be restored to their normal position in true alignment with the surrounding structure.

In the accompanying drawings, forming a 30 part of this specification, Figure 1 is a plan, partly in section, of a roadway at the point where a branch enters the main line. Fig. 2 is a vertical section through main-line slot of the same. Fig. 3 is a cross-section taken on 35 the line 1 2, Fig. 1, at a larger scale. Fig. 4 is a similar view taken on the line 3 4, Fig. 1, same scale. Fig. 5 is a detached detail, in perspective, of a single plate, hereinafter referred to.

40 In all the figures the same letters of reference are used to indicate the same parts.

The usual way of constructing and supporting these points has been to introduce pillars of iron of various shapes, unsupported 45 sideways and without means of adjustment when thrown out of alignment, these pillars forming part of the substructure, but so disconnected from their surrounding parts as to be capable of an independent movement, the 50 result being that frequently the point would be so far thrown out of line as to obstruct the passing grip or cause it to enter the wrong slot.

Indeed seldom have these points been found in proper relation with the surrounding road-bed after being in use where heavy vehicles 55 pass over them for any length of time.

The present invention overcomes these difficulties, the point being designed with an especial view of maintaining its position, however heavy may be the strain brought 60 upon it by the surface traffic.

In the drawings, A A are the slots—main and branch—in which the grip-shanks move, these slots being formed by the angle-irons *a* *a' a' a'*. The two adjoining center irons, *a' a'*, 65 are those to which the substructure of the point is secured.

B B are the yokes or frames of the subway, *b b* the frame-sills, and C the track-rails, these parts being constructed in any of the prevailing methods. 70

The point-support is formed by the two vertical side plates, D D, which conform to the shape of the slots they are related to with respect to their being straight or curved accordingly as the slots are straight or curved. 75 The upper edges of these plates will be bolted to the vertical flanges of the slot-irons *a' a'*, and also the plates will be bolted at their lower edges to the bars E, which stretch across 80 at least three of the yokes and are supported by and bolted to the cross-bars F, which in turn are made fast by bolts or rivets to the frames or yokes B. The rear ends of the plates D are joined by a diaphragm or cross- 85 plate, G, which is secured to the side plates through the medium of the angle-irons *g*, which are riveted to both.

H H are flat iron braces bolted to the plates D D and to the cross-bars F, and yoke-frames, 90 as shown. The bolts fastening the foot of each brace should be long enough to allow of thin plates or "shims" being inserted between the foot of each brace and the bar F, for by means of these shims the vertical adjustment of the point is effected. 95

I is a brace-rod which serves to adjust the point horizontally. This rod is secured to the plates D by being passed through them, and the projecting end having a head riveted thereon, a shoulder or collar being formed on the opposite side of the plates, and between the plates, to prevent them being drawn together, a short socket-piece, *i*, will be pro- 100

vided. The opposite end of this brace-rod will pass through the bar J, which bar is fastened to two adjoining yokes, as shown. Where the rod passes through the bar J it 5 will have a screw-thread cut upon it and nuts on each side of the bar, so that as these nuts are screwed back and forth so the rod and the attached point will be drawn in or forced out to the effect of nicely adjusting the point 10 horizontally. Care must be taken to place these rods below the path of the grip.

A single plate, as illustrated in Fig. 5, may 15 be substituted for the double plates D D by having the upper part of the plate slit into sections and these sections alternately bent to the left and right to join onto the slot-irons. In this case the end diaphragm is avoided, otherwise the remaining parts will 20 be the same.

20 K is the usual cover, which is bolted over the structure at the surface, but removable whenever it is desired to get at the substructure of the point to adjust it.

25 When the point terminates in a long movable tongue, L, as where a branch enters the main line, the usual steel tongue is provided and bolted to the main part of the point in the usual manner.

30 Where the bolts move in adjusting the point, the holes for them must be slotted holes. Thus where the feet of the braces H H are bolted to the cross-bars F at h and yoke-frames at h' the holes for the bolts will 35 be slotted holes to accommodate the vertical and horizontal adjustments.

In adjusting the point first loosen the bolts fastening the bars E to the cross-bars F, then loosen the bolts at the foot of the braces H, and then slack up the nuts on the brace-rods I until the point can be moved into the desired 40 position. Then put in shims wherever it may be found necessary and screw up all the nuts of the bolts tight again. For the purpose of getting at these bolts the cover K must be removed, as before suggested. 45

What I claim as my invention, and desire to secure by Letters Patent, is—

1. In street-railways having subways for the passage of the mechanism of the car—such as the grip in a cable road or collector 50 in an electric road—the substructure of the points which are bounded on each side by the diverging slots of either cross or branch lines, as herein described, consisting, essentially, of a vertical plate-iron point-support secured to 55 the yoke-frames, braced in a perpendicular position by diagonal braces and being adjustable horizontally and vertically, substantially as and for the purpose herein set forth and described.

2. The point-support herein described, consisting of a vertical plate, D, bars E and F, braces H, and rod I, in combination with the yoke-frames B, the whole arranged and connected substantially as and for the purpose 65 described.

WILLIAM S. PHELPS.
